[57] CLAIM

The ornamental design for an airplane, as shown and described.

DESCRIPTION

FIG. 1 is a front view of an airplane embodying my novel design;

FIG. 2 is a left side view thereof;

FIG. 3 is a right side perspective view taken from the front thereof;

FIG. 4 is a bottom view thereof;

FIG. 5 is a rear view thereof; and,

FIG. 6 is a top view thereof.

The broken lines in the drawings are for illustrative purposes only and the plane designation "328" form no part of the claimed design.

FIG. 1

FIG. 2

FIG. 3

FIG. 4

FIG. 5

FIG. 6
